TRAIN ORDER DELIVERY CRANE

Edward T. Ford, Red Key, Ind., assignor of one-half to H. F. Rogers, Red Key, Ind.

Application September 1, 1943, Serial No. 500,817

5 Claims. (Cl. 258—2)

This invention relates to a train order delivery crane, and has for the primary object the provision of a device of this character which may be easily and quickly adjusted to support one or more orders in position to be taken up by a moving train from either the front or rear end of said train or from both ends of the train and may be quickly brought into a position for re-loading or into a fully inoperative position when not desired for use.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which

Figure 1 is a side elevation, partly in section, illustrating a train order delivery crane constructed in accordance with my invention.

Figure 2 is a detail sectional view taken on the line 2—2 of Figure 1.

Figure 3 is a sectional view taken on the line 3—3 of Figure 1.

Figure 4 is a fragmentary plan view, partly in section, illustrating the journal for one of the crane arms and the means for limiting the rotation of the crane arm.

Figure 5 is a detail sectional view illustrating one of the latches engaging one of the journals.

Referring in detail to the drawing, the numeral 5 indicates a vertically arranged supporting post on which are pivotally mounted in superimposed and spaced relation plates 6 and 7 provided with journals 8 rotatably receiving shafts 9 and 10 each provided with an enlarged socketed end 11 to frictionally receive staffs 12 of order holders 13 and 14. The staffs 12 can be readily removed from the enlarged ends of the shafts and be placed therein. The walls of the sockets are shaped to receive angularly related faces of the staffs.

The shaft 9 is slightly longer than the shaft 10 and is provided with a hand grip 16 for the purpose of rotating said shaft 9 to change the positions of the order holder 13. The order holder 13 is of the double type permitting two orders to be carried thereby in a removable manner, either one of which may be brought into a position for delivery through the rotation of the shaft 9 by the hand grip 16. A collar 17 is secured on the shaft 9 and is provided with a lug 18 to engage a stop 19 formed on one of the

bearings or journals of the plate to limit the rotation of the shaft 9, the purpose of which is to permit the operator to bring either of the orders carried by the order holder 13 into position of delivery.

The plates 6 and 7 are connected by a tie rod 20 provided with a turn buckle 21 whereby the shafts 9 and 10 will be caused to swing in unison to assume either an upwardly and outwardly inclined position, as shown in full lines in Figure 1, for the purpose of arranging the orders in delivery position or into horizontal position, as shown in dotted lines whereby the staffs 12 may be easily detached from the shafts 9 and 10 for the purpose of having new orders applied thereto or to swing downwardly and outwardly from the post to position the shafts 9 and 10 in full inoperative position. When in this latter named position the staffs 12 and the order holders carried thereby are preferably detached from the shafts 9 and 10.

Latch plates 22 and 23 similarly constructed are pivotally mounted on the post 5 and are spring influenced to normally occupy latching position. The latch plate 22 is for the purpose of engaging the plate 6 for supporting the order holders in order delivery position, as shown in full lines in Figure 1, while the latch plate 23 is for supporting the shafts 9 and 10 horizontally and as indicated in dotted lines in Figure 1, so that the staffs and order holders thereof may be removed and replaced with ease.

The order holder 13 consists of a head 25 secured to the staff and has secured thereto pairs of fingers 26. The fingers of each pair are arranged in diverging relation and one finger of each pair is arranged in parallel relation to the corresponding finger of the other pair of fingers, as clearly shown in Figure 1. The free ends of the fingers have pivoted thereto spring clips 27 to engage flexible elements 28 to which the orders are secured.

Fasteners 29 are secured to the head 25 between the pairs of fingers, and are provided with resilient gripping portions 30 to frictionally receive and grip the flexible elements and coact with the spring clips 27 in supporting the flexible elements in triangular shaped form. The holder 14 includes a head 30 connected to the staffs 12 and diverging fingers 31 provided with spring clips 32 hinged thereto to engage the flexible element to which the order is secured and the flexible element is also engaged by a fastener 29 applied to the head 30.

In operation, with the device positioned and

the orders applied to the order holders, as shown in Figure 1, the device is arranged for the delivery of orders both to the front and rear end of a passing train. Also should the train be provided with double engines, the head 13 may have its position reversed by the rotation of the shaft 9 after one of the orders has been obtained by the crew of the first locomotive so as to bring the other order in position to be received by the crew of the second locomotive.

While I have shown and described the preferred embodiment of my invention, it will be understood that minor changes in construction, combination and arrangement of parts may be made without departing from the spirit and scope of the invention as claimed.

Having thus described the invention, what I claim is:

1. In a train order delivery crane, a vertical supporting post, journals pivotally mounted on the post in superimposed relation, shafts carried by said journals, means connecting the shafts for pivotal movement in unison, and order holders including staffs removably secured to said shafts.

2. In a train order delivery crane, a vertical supporting post, journals pivotally mounted on the post in superimposed relation, shafts carried by said journals, means connecting the shafts for pivotal movement in unison, order holders including staffs removably secured to said shafts, said shafts having three positions, one for supporting the order holders in order delivering position, another for supporting the order holders in position for removal and the other in a fully inoperative position, and pivotally mounted spring influenced latches carried by the post for

releasably securing the shafts in two of the stated positions.

3. In a train order delivery crane, a vertically arranged supporting post, plates pivoted on said post in superimposed spaced relation, tie means connecting said plates, journals on said plates, shafts carried by said journals and having socketed ends, and order holders including staffs received by the socketed ends of the shafts.

4. In a train order delivery crane, a vertically arranged supporting post, plates pivoted on said post in superimposed spaced relation, tie means connecting said plates, journals on said plates, shafts carried by said journals and having socketed ends, order holders including staffs received by the socketed ends of the shafts, and spring influenced latches pivoted on the post to engage the plates for releasably securing the plates in two of several positions occupied by the order holders.

5. In a train order delivery device, a vertically arranged supporting post, plates pivoted on said post, adjustable tie means connecting said plates, shafts journaled on said plates and having socketed ends, order holders including staffs removably received by the socketed ends of the shafts, one of said order holders including a head having pairs of fingers connected thereto and the other holder including a head having a pair of fingers connected thereto, spring clips pivotally connected to the fingers to engage and grip flexible elements carrying orders, and fasteners carried by the head and located between the fingers and provided with gripping portions to receive and grip the flexible elements.

EDWARD T. FORD.
